(57) **CLAIM**

The ornamental design for a “panel kit”, as shown and described.

DESCRIPTION

FIG. 1 is a front perspective view of a panel kit showing my new, original and ornamental design;

FIG. 2 is a front view;

FIG. 3 is a rear view;

FIG. 4 is a top view;

FIG. 5 is a bottom view;

FIG. 6 is a left side view;

FIG. 7 is a right side view;

FIG. 8 is an environmental view before application of the panel kit to an exemplary section of privacy fence shown in broken lines; and,

FIG. 9 is an environmental view after application thereof on a privacy fence, shown in broken line.
